UNITED STATES PATENT OFFICE.

JOHN M. THOMPSON AND WILLIAM H. THOMPSON, OF BUFFALO, NEW YORK.

ADJUSTABLE SEWER CLEANER.

Application filed December 8, 1921. Serial No. 521,024.

To all whom it may concern:

Be it known that we, JOHN M. THOMPSON and WILLIAM H. THOMPSON, citizens of the United States, residing at Buffalo, in the county of Erie and State of New York, have invented a new and useful Improvement in Adjustable Sewer Cleaners, of which the following is a specification.

This invention relates to sewer cleaners of the kind which are adapted to be drawn through a sewer pipe for the purpose of removing obstructions which may have accumulated therein, and more particularly to sewer cleaners of this kind which are adjustable to fit into sewers of different sizes.

The objects of the invention are to provide a sewer cleaner of this kind having means of improved construction for adapting the same to operate on sewers of different diameters; also to improve the construction of adjustable sewer cleaners for the purpose of producing a strong, rigid, and comparatively inexpensive sewer cleaner which can be easily adjusted to the desired size; also to provide the various parts of the sewer cleaner with sharpened edges which assist in cutting obstructions in a sewer; also to provide a cleaner of this kind which is so constructed that the parts thereof can be rigidly held in any adjusted position, so that the cleaner may be drawn through a sewer in either direction; also to improve the adjustable sewer cleaners in other respects hereinafter specified.

In the accompanying drawings:

Figs. 1 and 2 are side elevations of an adjustable sewer cleaner embodying the invention, Fig. 1 showing the parts of the same adjusted to fit a small sewer and Fig. 2 showing the same adapted to fit a larger sewer.

Figs. 3 and 4 are longitudinal sectional elevations thereof showing the parts in different positions.

Fig. 5 is a rear end view thereof when the parts are positioned as shown in Fig. 3.

Figs. 6 and 7 are transverse sectional elevations thereof on lines 6—6 and 7—7 respectively, Fig. 3.

Fig. 8 is a rear end view thereof when the parts are in the position shown in Fig. 4.

The sewer cleaner includes a substantially central body portion on which the adjustable parts of the cleaner are mounted and which is adapted to receive the draft strains

to which the cleaner is subjected. This body portion may be of any suitable or desired construction, that shown including a plurality of angle bars A four being used in the construction shown, which extend lengthwise of the cleaner and the ends of which are rigidly secured to front and rear fittings or end pieces B and C. The angle bars in the construction shown are so arranged that the legs of the bars form four spaces or channels and for this purpose, the angle bars are fitted into rectangular depressions formed between radially extending arms b and c of the end pieces, and may be secured to the arms by any suitable means, such for example, as rivets a. In order to help in clearing a sewer of obstructions, the front edges of the angle bars are preferably sharpened to form cutting edges, as shown at a'. The front end piece B is also provided with a forwardly extending lug or part b¹ to which the clevis or other attaching means b² may be secured, for example, by means of a bolt b³ extending through the projection b¹, Figs. 2 and 3. The rear end piece is provided with a corresponding projection c¹ which is preferably hollow and which is also provided with holes adapted to receive a bolt c² for attaching a clevis c³ to the rear end piece or fitting. These end pieces consequently serve for the two-fold purpose of holding the angle bars of the body in correct relation to each other and also of affording means for attaching draft devices thereto. End pieces or fittings of other suitable or desired construction, however, may be provided.

The sewer cleaner is provided with a plurality of horizontal shoes or guide bars D which are adapted to engage the inner walls of the sewer and which serve the two fold purpose of guiding the cleaner in its movement through a sewer and also of cutting deposits formed in the sewer. These shoes or guide bars may be of any suitable or desired construction, those shown being provided with web portions d which are arranged in substantially radial planes with reference to the body of the sewer cleaner and the intermediate portions of the shoes or cutting bars are provided with substantially circumferential flanges d¹ which afford a somewhat extended bearing on the inner surface of the sewer. In order to facilitate the cutting of deposits from the

sewer, the opposite sides of the flanged portions d^1 are preferably sharpened as indicated at d^2 , thus providing both radial and circumferential cutting edges. Any desired number of shoes or guide bars may be provided, four being shown in the construction illustrated, which have the function of dividing the deposit in the sewer into four parts and thereby facilitate the removal thereof.

The shoes or guide bars may be adjusted relatively to the central body portion of the sewer cleaner in any desired manner. In the construction shown for this purpose, each shoe or guide bar is connected to the flanges of two adjacent angle bars A by means of two or more parallel links E, the outer ends of which are pivotally connected adjacent to the end portions of the shoes D by means of pivots e or the like. The inner ends of the parallel links are connected to the flanges of the angle bars A, by means of pivots e'. These links are also preferably provided with sharpened front and rear edges e^2 which greatly assist in cutting the deposit in the sewer, particularly in view of the fact that these links are generally arranged in angular relation with reference to the body portion of the sewer cleaner, so that a gradual entrance of the cutting edges into the deposit is effected. The parallel links connecting the body portion with the guide shoes may be of any suitable construction, those shown including hub portions e^3 arranged between flanges of adjacent angle bars and pivoted thereto, and bifurcated outer portions, the ends of which straddle the webs d of the shoes and are pivoted thereto.

The adjusting of the guide shoes or bars with reference to the central body portion of the cleaner may be effected in the construction shown, by means of toggle or adjusting links F, a pair of these links being provided in the construction shown, for each of the guide shoes, the outer ends of which are connected to the flange d of the guide shoe by means of a pivot e, and the inner ends of the links are pivotally connected to an adjusting block or nut F', which in the construction shown is movable lengthwise of the body portion of the sewer cleaner. The adjusting block shown, see particularly Fig. 6, has angle shaped recesses f into which the corners of the angle bars A are adapted to enter for guiding the block F' in its movement, and this block is also preferably provided with outwardly extending arms or projections f' to which the inner ends of the toggle links F are pivotally connected. It will be readily seen that by moving the adjusting block lengthwise of the body portion of the sewer cleaner, the guide shoes may be adjusted toward and from the body portion of the

cleaner to adapt the same to operate on sewer pipes of different diameters.

Any suitable or desired means may be provided for moving the adjusting block relatively to the body portion of the cleaner and for holding the same in any desired position. In the construction shown for this purpose, a central screw shaft G is provided having a threaded portion which engages a correspondingly threaded central hole in the adjusting block or nut. The ends of the screw shaft are suitably journalled in the end pieces or fittings B and C, a bearing collar g being preferably arranged adjacent to the front fitting B which is adjustable to take up any slack or lost motion which may occur in the screw shaft. The shaft is also provided adjacent to its other end with a bearing collar g', and extends through the rear end piece or fitting C and into the recessed portion thereof, and this end of the screw shaft is provided with an end g^2 which is preferably squared or otherwise formed to receive a wrench or key, not shown, for turning the shaft to move the adjusting block nut in either direction and thereby to adjust the sewer cleaner for sewers of different diameters. Any other means for adjusting the position of the block F' may be provided.

The sewer cleaner is preferably also provided with a gaging, reinforcing and cutting member H which, in the construction shown, is in the form of a disk and is adapted to engage the material accumulated in the sewer and push the same through the sewer to a part thereof where this material can be removed. In the construction shown for this purpose, the member or disk H is provided with an annular, forwardly extending flange h provided with a plurality of cutting teeth h'. Since it is desirable that this cutting and pushing disk should be of a size slightly smaller than the diameter of a sewer to be cleaned, it is desirable that a plurality of these disks be provided, one for each different size of sewer to be cleaned and these disks are so mounted on the body portion of the sewer cleaner that they can be readily secured thereto or removed therefrom. For this purpose, those cutting members which are used in connection with sewer pipes of relatively large diameters are, in the construction shown, arranged to be secured on the angle bars A of the body portion. The cutting disks of larger diameter are provided with central apertures through which the rear end of the body portion is adapted to extend and with rearwardly extending portions or lugs h² adapted to enter between the legs of the angle bars A. One or more of these lugs is provided with a set screw h³ for clamping the cutting disk in place on the body portion. The cutting disks of smaller diameter are provided with

flange portions h^4 having set screws h^5 adapted to engage with the rearwardly projecting portion of the rear fitting C. In the use of the sewer cleaner, this annular cutting flange h serves the purpose of severing the deposit in the sewer pipe adjacent the inner faces of the pipe, and the disk shaped portions thereof engage the accumulations in the pipe and force them lengthwise of the sewer into a portion thereof where the accumulations may be removed.

The annular cutting members H serve further purposes in connection with the adjustable cleaner. In the first place, the members 15 H engage the rear ends of the guide shoes or bars D, and thus reinforce these portions thereof, and secondly the cutting members form gages by means of which the cleaner may readily be set for sewers of the desired 20 diameter. For this purpose, the members H in the construction shown, are provided with a plurality of substantially radial recesses or notches I extending inwardly from the outer edges thereof, four of these recesses being 25 shown in the construction illustrated, in which the radial flanges d of the guide shoes or bars are adapted to seat. Consequently in adjusting the sewer cleaner for a particular sewer, a cutting disk of the desired size is selected and is placed into operative relation 30 to the body portion of the cleaner. The screw shaft G is then turned in such a manner as to move the flanges d of the guide shoes into the recesses I of the cutting disk. 35 When the radial flanges d of the guide shoes seat in the bottoms of the recesses I the sewer cleaner is correctly adjusted for the corresponding size of sewer and furthermore the rear ends of the guide shoes are strongly 40 braced to resist the strains or pressure to which they may be subjected. The front ends of the guide shoes are better reinforced against pressures or strains owing to the fact that these ends of the shoes are connected to 45 the body portion of the cleaner by means of two sets of links namely the front links E and the toggle links F.

In the use of the sewer cleaner, a cable or other draft device is attached to the front 50 clevis b^2 thereof and the device is drawn through the sewer to be cleaned. The deposit in the sewer is then cut by the radial cutting edges a' of the angle bars A, the front cutting edges e^2 of the front and rear 55 parallel links E and the radial cutting edges d^2 of the guide shoes, as well as the longitudinal cutting edges of the outer flanges of the shoes. The deposit in the sewer is further cut by means of the cutting teeth h' of 60 the cutting disks and these disks also push the loosened deposit lengthwise of the sewer. The many cutting edges provided on the sewer cleaner make the cleaner particularly desirable for clearing sewers of tree roots 65 which have grown into the same, as well as

for removing any other deposits which may form in the sewers. If, for example, a hard deposit is formed on a sewer, due to the deposit of chemicals or other materials therein, the cleaner may be drawn through the sewer, 70 a number of different times, the cleaner at first being contracted in diameter and being increased in diameter after each passage through the sewer, until the same is as large as can be used in connection with the 75 sewer. In this manner the deposits can be gradually cut away. Owing to the fact that the cutting edges a' , e^2 and d^2 flare or incline outwardly and rearwardly with reference to the body portion of the cleaner, the cutting 80 of deposits, roots or the like from a sewer is greatly facilitated, since a smaller end of the sewer cleaner enters the deposit in advance of the portion thereof of larger diameter.

By means of the construction shown, a single sewer cleaner can be used on a large number of different sized sewers and the cleaner can be very quickly adjusted to co-operate with sewers of different sizes. The 85 construction of the cleaner is such that the parts thereof are rigidly held in any position into which they are set, so that the cleaner may be drawn through the sewer in either direction. Consequently, if the cleaner 90 cannot be pulled through the sewer, due to the obstructions therein, it can be withdrawn in the opposite direction.

We claim as our invention:

1. In a sewer cleaner, the combination of a 100 central body portion, guide shoes adapted to engage with a sewer pipe, radial connecting parts supporting said guide shoes from said body portion, said connecting parts and guide shoes being adapted to cut the deposit 105 in a sewer pipe into a series of sector-shaped portions, and means for holding said radial connecting parts in different positions relatively to said shoes and body portion to adapt the sewer cleaner to operate on sewers 110 of different sizes.

2. In a sewer cleaner, the combination of a 115 central body portion, guide shoes adapted to engage with a sewer pipe, radial connecting parts supporting said guide shoes from said body portion, said connecting parts being adapted to make a series of cuts in the deposit in a sewer pipe, which cuts extend substantially from the center to the inner surface of the sewer pipe, and a disk arranged 120 on the rear end of said sewer cleaner and having a plurality of circumferential teeth which cut the deposit from the surface of a sewer pipe and push the same lengthwise of the pipe.

3. A sewer cleaner having cutting members which are arranged to cut the deposit in a sewer into a series of sector-shaped portions, and a disk arranged on the rear end 125 of the sewer cleaner and having circumfer-

ential cutting means which cut the deposit adjacent to the surface of a sewer pipe, the body portion of said disk serving to push the cut material lengthwise of the pipe.

4. A sewer cleaner having radial pivoted cutting members which are arranged to cut the deposit in a sewer into a series of sector-shaped portions, means for pushing said portions lengthwise of a sewer, and means for holding said cutting members in different angular relations to the sewer cleaner to adapt the same to operate on sewers of different diameters.

5. In a sewer cleaner, the combination of 15 a central body portion, an adjusting screw arranged thereon, guide shoes movable to different distances from said body portion, a pair of parallel links connecting each guide shoe with said body portion, an adjusting block movable lengthwise on said body portion and co-operating with said adjusting screw, and toggle links connecting said adjusting block and said guide shoes.

6. In a sewer cleaner the combination of 25 a central body portion, a plurality of guide shoes adjustably mounted thereon, a pair of parallel links connecting each guide shoe with said body portion, a block adjustably mounted on said body portion, an adjustable screw for holding said block in different positions on said body portion, and means connecting said block and said shoes for positioning said shoes at different distances from said body portion.

35 7. In a sewer cleaner the combination of a central body portion, a plurality of guide shoes adjustably mounted thereon, parallel links connecting said body portion and said guide shoes, a pair of parallel links connecting each guide shoe with said body portion, an adjusting block movably mounted on said body portion means connecting said block with said shoes for determining the positions thereof relatively to said body portion, 45 and means for rigidly securing said block to said body portion.

8. In a sewer cleaner the combination of a central body portion, a plurality of guide shoes adjustably mounted thereon, parallel 50 links connecting said body portion and said guide shoes, for guiding the movement of said guide shoes relatively to said body portion, an adjusting block movably mounted on said body portion, toggle links connecting said shoes and said blocks for adjusting the positions of said shoes relatively to said body portion, and means for rigidly securing said block on said body portions to hold said shoes in their adjusted positions.

60 9. In a sewer cleaner the combination of a central body portion, a plurality of guide shoes adjustably mounted thereon, and having sharpened edges to cut deposit in a sewer near the inner surface of the sewer, means 65 on said body portion for rigidly holding

said guide shoes at different distances from said body portion, and provided with cutting portions extending radially in said sewer, and a member detachably mounted on the rear end of said body portion and adapted to push through the sewer the material loosened by said cleaner.

70 10. In a sewer cleaner the combination of a central body portion, a plurality of guide shoes adjustably mounted thereon, means 75 on said body portion for rigidly holding said guide shoes at different distances from said body portion, and a plurality of disks of different diameters, any one of which is adapted to be mounted on said body portion 80 to push material through the sewer.

11. In a sewer cleaner, the combination of 85 a central body portion guide shoes adapted to be moved to different distances from said body portion, and a plurality of disks of different diameters, any one of which is adapted to be mounted on said body portion and to engage with said shoes for holding the same at a definite distance from said body portion.

90 12. In a sewer cleaner, the combination of 95 a central body portion guide shoes adapted to be moved to different distances from said body portion, and a member adapted to be secured on said body portion and the outer edges of which are adapted to engage the inner portions of said guide shoes.

13. In a sewer cleaner, the combination of 100 a central body portion guide shoes adapted to be moved to different distances from said body portion, and a disk having a part adapted to be secured to said body portion, and recesses in the outer portion thereof into which parts of said guide shoes are adapted 105 to enter for holding the guide shoes in fixed relation to said body portion.

14. In a sewer cleaner, the combination of 110 a central body portion guide shoes adapted to be moved to different distances from said body portion, a member adapted to be secured on said body portion and the outer edges of which are adapted to engage the inner portions of said guide shoes, and a plurality of cutting teeth at the outer edge of 115 said disk which extend forwardly from said disk.

15. In a sewer cleaner, the combination of 120 a central body portion, a plurality of guide shoes adjustably mounted thereon, means on said body portion for rigidly holding said guide shoes at different distances from said body portion, and a guide member adapted to be secured on said body portion and the outer portions of which are adapted to engage said shoes, whereby said shoes may 125 be drawn into engagement with said guide member for positioning the shoes relatively to said body portion.

16. In a sewer cleaner, the combination of 130 a body portion comprising a plurality of

- flanged bars spaced apart, front and rear draft pieces to which said bars are connected, and guide shoes mounted on the flanges of said bars.
17. In a sewer cleaner, the combination of a body portion comprising a plurality of flanged bars spaced apart, front and rear draft pieces to which said bars are connected, and which space said bars apart, guide shoes mounted on said bars, and means mounted in the space between said bars for adjusting said guide shoes toward and from said body portion.
18. In a sewer cleaner, the combination of a body portion comprising a plurality of flanged bars spaced apart, front and rear draft pieces to which said bars are connected, and which space said bars apart, guide shoes mounted on said bars, links connecting said guide shoes and the flanges of said bars, and means arranged in the space between said bars for holding said links in different angular positions to adjust said shoes relatively to said body portion.
19. In a sewer cleaner, the combination of a body portion including a plurality of substantially parallel bars, end pieces connecting the opposite ends of said bars, and adjusting screw journalled in said end pieces, guide shoes adapted to be positioned at different distances from said body portion, and means connecting said adjusting screw and said guide shoes.
20. In a sewer cleaner, the combination of a body portion including a plurality of substantially parallel bars, end pieces connecting the opposite ends of said bars, and adjusting screw journalled in said end pieces, guide shoes, links connecting said bars and said guide shoes, and adjusting nut cooperating with said screw and guided on said bars, and means connecting said guide shoes and said adjusting nut for adjusting said shoes relatively to said body portion.
21. In a sewer cleaner, the combination of a body portion including a plurality of parallel bars, guide shoes, links pivotally connected with said guide shoes and said bars, and means for adjusting said guide shoes relatively to said body portion, said links and the front ends of said bars and shoes being provided with cutting edges.
22. In a sewer cleaning device, the combination of a body portion, guide shoes mounted on said body portion and which are provided with a substantially radial flange having cutting faces at an end thereof and with a substantially circumferential flange provided with cutting edges at the sides thereof.
23. In a sewer cleaner, the combination of a body portion, guide shoes, links connecting said guide shoes and said body portion, and a disk mounted on said body portion and having forwardly extending cutting teeth, said body portion, said links and said guide shoes also being provided with cutting edges.
24. In a sewer cleaner, the combination of a body portion including a plurality of parallel bars, guide shoes, links pivotally connected with said guide shoes and said bars, means for adjusting said guide shoes relatively to said body portion, said links and the front ends of said bars and shoes being provided with cutting edges, and a member mounted on the rear portion of said body portion and adapted to push through the sewer the material cut therefrom.
25. In a sewer cleaner, the combination of a body portion including a plurality of parallel bars, guide shoes, links pivotally connected with said guide shoes and said bars, means for adjusting said guide shoes relatively to said body portion, said links and the front ends of said bars and shoes being provided with cutting edges, and a member mounted on the rear portion of said body portion and adapted to push through the sewer the material cut therefrom, said member also having a substantially annular cutting edge adapted to sever material adjacent to the walls of the sewer.
26. In a sewer cleaner, the combination of a central body portion, guide shoes, pairs of parallel links connecting each guide shoe and said body portion near the front and rear ends of said guide shoe, whereby said shoes may swing toward and from said body portion, an adjusting link for each shoe connected with said body portion and with one end of the shoe, and a disk mounted on said body portion and adapted to be engaged by the other ends of said shoes.
27. A sewer cleaner having cutting members which are arranged to make a series of substantially radial cuts in a sewer and arranged at an angle so that the middle portion of the deposit will be cut first, means on said sewer cleaner for making a substantially circular cut adjacent to the wall of the sewer pipe, and means for pushing the cut material lengthwise of a sewer.

JOHN M. THOMPSON.
WILLIAM H. THOMPSON.

Certificate of Correction.

It is hereby certified that in Letters Patent No. 1,446,224, granted February 20, 1923, upon the application of John M. Thompson and William H. Thompson, of Buffalo, New York, for an improvement in "Adjustable Sewer Cleaners," errors appear in the printed specification requiring correction as follows: Page 4, line 29, claim 6, for the word "adjustable" read *adjusting*; same page, lines 39 and 40, claim 7, strike out the comma and words ", a pair of parallel links connecting each *guide shoe* with said body portion" and insert instead *for guiding the movement of said guide shoes relatively to said body portion*; and that the said Letters Patent should be read with these corrections therein that the same may conform to the record of the case in the Patent Office.

Signed and sealed this 1st day of May, A. D., 1923.

[SEAL.]

KARL FENNING,
Acting Commissioner of Patents.
